Patented Sept. 7, 1920.

2 SHEETS—SHEET 2.

UNITED STATES PATENT OFFICE.

HARRY ROOS PALMER, OF HARRISBURG, PENNSYLVANIA.

SMOKE-FILTER AND FORCE-DRAFT DEVICE FOR FURNACES.

1,352,142.

Specification of Letters Patent. Patented Sept. 7, 1920.

Application filed August 15, 1919. Serial No. 318,431.

To all whom it may concern:

Be it known that I, HARRY R. PALMER, a citizen of the United States, residing at Harrisburg, in the county of Dauphin and State of Pennsylvania, have invented certain new and useful Improvements in Smoke-Filters and Force-Draft Devices for Furnaces, of which the following is a specification.

10 My invention relates to improvements in a combined smoke filterer and force draft device for furnaces.

The object of this invention is to provide an apparatus in which the cinders, soot and heavy gases are thoroughly washed from the discharge of the furnace and this washing operation, taking all of the heavy particles from the furnace discharge, lightens the remaining portion, which results in the more rapid flow thereof through the stack and thus increases the capacity of the stack without increasing the size thereof, and which necessarily increases the draft of the furnace.

25 Another object of my invention is to provide an apparatus of this character which can be readily applied to the ordinary furnace and which has certain details of structure and operation herein-after more fully set forth.

In the accompanying drawing Figure 1 is a transverse horizontal sectional view of a furnace flue and stack showing my improved apparatus applied thereto.

35 Fig. 2 is an enlarged vertical view taken on the line 2-2 of Fig. 1.

Fig. 3 is an end view broken away.

Referring now to the drawings; 1 represents the furnace flue which is connected to a furnace of the character in which the load thereon is rapidly varied and therefore it is necessary to rapidly increase the fuel consumption and the output of the furnace and by my apparatus the draft of the furnace is instantaneously increased in either a forced draft furnace or a natural draft, and thus increase the output of the furnace. The flue 1 is connected to the stack 2 which is shown of a brick form, and which is usually of a considerable length to increase the draft of the furnace.

Connected to the flue 1 intermediate the furnace and stack at an angle is a pipe 3 having a vertical partition 4 forming the

two flues 5 and 6. The flue 1 is provided with a damper 7 opposite the portion 4 whereby the discharge of the furnace can be allowed to either pass direct to the stack 2 or diverted into the flue 5. The flues 5 and 6 are provided with dampers 8 and 9 whereby the draft through the same can be readily regulated.

The outer end of the flue is connected to the vertical flue 10 which is preferably made of cement so as to be perfectly watertight. The side walls 11 and 12 of the flue 10 are provided with spray jets or nozzles 13, which are staggered so the spray from the nozzles on one side will overlap the spray from the nozzles on the opposite sides and whereby the entire interior of the flue 10 is covered by the spray to fully wash the gases as they pass through the flue. The jets or nozzles 13 are connected to the supply pipes 14 and 15 through which either steam or water may pass to the jets or nozzles.

The lower end of the flue 10 is connected to elongated tank 16 formed continuous therewith and in which is maintained a predetermined water level the purpose of which will be later described. Beyond the lower end of the flue 10 the tank 16 is provided with a covered portion 17 the outer walls of which are extended downwardly as indicated at 18 into the water in the tank so as to form a seal to prevent the gases from passing from the tank. The tank beyond the wall 18 is open as clearly shown in Fig. 2 of the drawing. The end wall 20 of the open portion of the tank is provided with a series of pipes 21, 22 and 23 communicating therewith, one above the other and are provided with spigots 24 and each succeeding spigot extends slightly beyond the other so that the discharge of the water from the spigot above will not discharge on the spigot below.

The side of the tank is provided with a discharge pipe 25 by means of which the water and cinders, etc., may be discharged therefrom. The said pipe is provided with a valve 26 having an arm 27 the outer end of which is provided with a horizontally extending pin 28. Pivoted carried by the end of the tank below the spigots is a lever 29 which extends parallel with the discharge pipe and has in one end an elongated slot through which the pin 28 extends. The lever 29 as shown is intermediately pivoted

at 31 and the other end is provided with a cup shaped member 32, arranged directly below the spigots and when the cup is filled the lever is rocked for opening the valve 26 for allowing the water, cinders, etc., to flow from the tank and whereby a maintained water level is provided in the tank as will be hereinafter more fully described.

The covered portion 17 of the tank is provided with an opening 33 which communicates with the fan housing 34. The upper end of the fan housing is in communication with the funnel shaped member 35, which has its upper end in communication with the lower end of the flue 6, and by means of which an additional draft is created. It may not be found necessary to employ a fan in which event the funnel shaped member will be of the shape shown in dotted lines Fig. 2, and extend down and communicate directly with the opening 33 in the closed portion of the receptacle.

In operation the damper 7 is in the position shown in Fig. 1 of the drawings which causes the smoke, gases, etc., to pass into the flue 5, and thence downwardly through vertical flue 10. In its passage through this flue 10, the cinders, soot, etc., are thoroughly saturated with steam or water whichever is found desirable and fall into the water in tank 16. This will relieve the discharge of the furnace of all heavy particles and make it much lighter which increases the draft in the stack and necessarily causes a greater fuel consumption. This also makes the discharge of the furnace much lighter in color which in some localities is very essential. The water from the spray nozzles keeps the tank filled to its predetermined level which is very close to the lower end of the wall of the flue so that a portion of the smoke and gases practically pass through the body of water. The fan aids passage of the smoke and gases around the lower end of the wall and draws it upwardly and discharges it into the lower end of the flue 6. It then passes from the flue 6 to the flue 1 beyond the damper to the stack 2. Under normal running of the furnace when it makes no difference about the color of the smoke discharged from the stack, the damper 7 is turned lengthwise of the flue 1, and the smoke passes direct to the stack.

The spigot 24, carried by one pipe is opened, that is the one carried by the pipe arranged at the desired level so that as soon as the water reaches said pipe it flows from the tank and fills the cup shaped member 32, so that the weight of the water therein overbalances the valve 26, opening the same through the medium of the levers 27 and 29, so that the water will flow from the tank through the pipe 25 carrying with it the cinders and other deposits in the tank. The cup shaped member 32 is provided with an

opening to allow the water to gradually flow therefrom and whereby the valve 26 is closed and prevents the water from passing from the tank until it has reached the predetermined level.

This arrangement of parts insures a perfect washing of the gases to lighten the discharge of the furnace so that the draft of the stack will be increased. In the event that the fan is not used, the natural draft of the stack draws the smoke and gases down through the flue around the wall and upwardly through the flue 6 and the smoke and gases having been freed of all solids, the draft in the stack is greatly increased.

Having thus described my invention, what I claim and desire to secure by Letters Patent, is:—

1. An apparatus of the character described, comprising a housing having an inlet at its upper end, spray nozzles arranged in the sides of the housing, a tank in communication with the lower end of the housing, and having a portion thereof closed, and having a discharge opening in its upper end, a baffle plate between the housing and discharge opening, and means for maintaining a predetermined water level in said tank.

2. An apparatus of the character described comprising a housing having an inlet at its upper end, spray nozzles arranged in the sides of the housing, a tank below the housing and in communication therewith, and extending beyond one side thereof, and a portion having a closed upper end and having a discharge opening therein, a baffle plate extending downwardly from the closed end of the tank intermediate the housing and the discharge opening, a discharge at the lower end of the tank, a valve in said discharge and means operated by the overflow of the tank for opening the valve and maintaining the water at a predetermined level.

3. An apparatus of the character described, comprising a housing having an inlet at its upper end, spray nozzles arranged in the sides of the housing, a tank below the housing and in communication therewith and extending beyond one side thereof, and a portion of the tank having a closed upper end sealed with the water in the tank, a fan in communication with the upper end of the closed portion of the tank, a discharge at the lower end of the opened portion of the tank, a valve controlling said discharge, and means operated by the overflow of the tank for opening the valve and maintaining the water at a predetermined level.

4. An apparatus of the character described, comprising a tank having a smoke inlet and discharge spray nozzles for washing the smoke, a water discharge at the lower end of the tank, a valve controlling

said discharge, an intermediately pivoted lever on the outside of the tank, means connecting one end of the lever to the valve, a cup shaped member carried by the opposite end of the lever, and a series of spigots communicating with the tank above the cup shaped member, substantially as described.

In testimony whereof I affix my signature in the presence of two witnesses.

HARRY ROOS PALMER.

Witnesses:

FLORENCE RAUCH,
G. L. GULLMERRY.

It is hereby certified that in Letters Patent No. 1,352,142, granted September 7, 1920, for an improvement in "Smoke-Filters and Force-Draft Devices for Furnaces," the name of the patentee is erroneously written and printed as "Harry Roos Palmer," whereas said name should have been written and printed as *Harry Root Palmer*; and that the said Letters Patent should be read with this correction therein that the same may conform to the record of the case in the Patent Office.

Signed and sealed this 17th day of May, A. D., 1921.

[SEAL.]

T. E. ROBERTSON,

Commissioner of Patents.
